APPARATUS FOR DREDGING

Charles T. Smith, The Dalles, Oreg.

Application February 24, 1936, Serial No. 65,276

1 Claim. (Cl. 37—71)

This invention relates generally to dredging, and particularly to a method of and apparatus for removing material from the bottom of a river or lake.

5 The main object of this invention is the construction of an apparatus and the practice of a method of removing material from a river or lake bed and delivering it to another point.

The second object is the employment of a 10 scraper for dredging operations in a manner that it will not merely dig a ditch in the river bed but will serve to level off the bottom of the river bed to a predetermined depth.

The third object is the utilization of a floating 15 vessel for supporting and propelling the dredging scraper.

These, and other objects, will become more apparent from the specification following as illustrated in the accompanying drawings, in 20 which:

Fig. 1 is a side elevation of the device showing the scraper in a dredging position in full lines and showing the scraper in conveying and discharging positions in dotted lines.

25 Fig. 2 is a plan of Fig. 1.

Fig. 3 is a perspective view of the scraper employed.

Fig. 4 is a plan showing a portion of a shore 30 line and showing the dredge in a digging position.

Fig. 5 is a fragmentary view showing the portion of a shore line on which is located a gravel collecting hopper.

Referring in detail to the drawings, there is 35 shown a shallow draft boat 10, preferably driven by a paddle wheel 11, and steered by means of the rudder 12. The boat 10 is provided with a boom 13 one end of which is hingedly mounted on the boat 10 on the pivot 14. On the rear end 40 of the boom 13 is mounted a sheave 15. Between the sheave 15 and pivot 14 is a second sheave 16. Attached to the outer end of the boom 13 is a boom handling line 17 which is operated by means of a cable winding drum 18.

45 The dredge bucket 19 is preferably of the type shown in Fig. 3 and is provided with a pair of bails 20 and 21. To the bail 20 is attached the rearmost bucket line 22 which passes over the sheave 15 to the cable winding drum 23. To the forward or digging end 24 of the bucket 19 is attached the bail 21 to which is secured the forward bucket line 25 which passes over the sheave 16 to the cable winding drum 26.

To the forward end 24 of the bucket 19 are 50 also secured the hitch links 27. To each link 27

is secured a bucket hauling line 28 which is secured to the bow of the boat 10 to the manually operated winch 29.

In order to illustrate the use of this invention there is shown a body of water 30 on whose 5 shore 31 is disposed a gravel bunker 32.

The operation of the device is as follows:

The bucket 19 is lowered by manipulation of the cable winding drums 23 and 26 until its teeth 33 engage the bottom 34 of the body of 10 water 30. The lines 28 have been adjusted to a length which will hold the bucket 19 in substantially the position shown in full lines in Fig. 1 during the digging operation, and the boat 10 is moved ahead under the power of the paddle 15 wheel 11 causing the bucket 19 to fill.

The lines 22 and 25 are then hauled in by their respective drums 23 and 26 and the bucket 19 raised to the position shown in dotted lines, as 19A in Fig. 1, which is just clear of the water, 20 and the boat 10 is then propelled to its destination, as shown in Fig. 5, and the bucket 19 elevated to the position shown as 19B to clear the bunker 32. The forward line 25 is then permitted 25 to pay out causing the end 24 to drop and discharge the bucket load into the bunker 32, and the boat 10 is then returned to the dredging site for another load.

This style of apparatus is especially adapted 30 for use in swift running waters and for a limited length of haul under which conditions it possesses numerous advantages not findable in other types of equipment. In swift running waters, for example, buckets like the clamshell or orange 35 peel bucket are inclined to capsize and not fill properly. The main objection to the Bagley type of scraper lies in the fact that it tends to dig a narrow channel instead of leveling off the bottom of the channel as is commonly desired. Also by means of the scarifier teeth 35, there is a 40 general loosening and leveling action taking place at each passage of the bucket 19.

While I have illustrated and described the device as being used in connection with a gravel 45 bunker 32, it must be understood that the bucket 19 may be discharged upon scows or upon the shore line or its load dropped into the water at a point more desired from the one which it is taken. It must also be understood that the boom 13 and the cable winding drums 18, 23 and 26 50 and the winch 29 may be mounted upon a scow, which in turn is propelled by a power boat without departing from the spirit of this invention.

I claim:

In an apparatus of the class described, the combination of a self-propelled boat having a driving means at one end thereof and having a boom projecting longitudinally from the opposite 5 end thereof, a dredge bucket having its cutting edge facing the propelling end of the boat and having cables for attaching the cutting end of said bucket to the propelling end of said boat,

a pair of sheaves mounted on the projecting end of said boom, cable-winding mechanisms mounted on said boat having cables passing over said sheaves to the front and rear ends of said bucket, and means for operating said cable-winding mechanisms independently. 5

CHARLES T. SMITH.
